ATTORNEY

UNITED STATES PATENT OFFICE.

NATHAN HOROWITZ, OF BROOKLYN, NEW YORK.

DESIGN FOR A BEAM LIGHT FOR LIGHTING FIXTURES.

Application filed November 10, 1924. Serial No. 11,336. Term of patent 3½ years.

To all whom it may concern:

Be it known that I, NATHAN HOROWITZ, a citizen of the United States, residing at Brooklyn, in the county of Kings and State of New York, have invented a new, original, and ornamental Design for a Beam Light for Lighting Fixtures, of which the following is a specification, reference being had to the accompanying drawing, forming part thereof, in which—

Fig. 1 is a side elevation showing my new design, and

Fig. 2 is a bottom plan view showing my new design.

I claim:

The ornamental design for a beam light for lighting fixtures, as shown.

NATHAN HOROWITZ.
